LOCK MECHANISM

Andrew Main, Cleveland, Ohio, assignor, by mesne assignments, to Cleveland Safe Box and Four-Way Lock Co., Cleveland, Ohio, a corporation of Ohio

Application July 6, 1931, Serial No. 548,733

7 Claims. (Cl. 70—78)

My invention relates to a lock mechanism and, particularly, to a lock mechanism adapted for use in prisons, as, for instance, on individual confinement cells and corridor doors, although it is not limited thereto. It is the object of my invention to provide a lock mechanism of the above type in which the parts of the lock mechanism are so arranged and the lock so constructed that turning of the usual key to operate the lock bolt actuating mechanism will result in instantaneous initiation of movement of the locking bolt toward full locked or full unlocked position, with the bolt being initially moved toward full locked position with maximum power and speed.

A lock wherein movement of the usual key to cause actuation of the lock bolt operating parts will cause instantaneous movement of the locking bolt is highly desirable, particularly in prison use, where a guard's or keeper's safety depends at times on the ability to quickly lock the prisoners in their confining cells. Such instantaneous bolt movement and thus quick locking is, in this instance, accomplished by use of a lock necessitating only a 90° throw of the key and roll back to move the bolt from one extreme position to the other. However, most previous locks employed in prisons have been of the type necessitating a 360° movement of the key with only 180° of that movement being effective on the lock bolt, the remainder of the movement of the key being for the purpose of taking up lost motion in the bolt operating parts. This has been unsatisfactory due to the length of time necessary for actuating the lock bolt sufficiently to confine a prisoner in a cell.

Likewise, it is desirable to have a lock actuating mechanism which will permit the locking bolt to be moved toward full locked position with the maximum power and speed, as well as having the lock actuating mechanism such that the locking bolt will be instantaneously moved toward full locked position on movement of the key. The maximum power for and speed of operation of the locking bolt are desirable in that recalcitrant prisoners are apt to attempt to block movement of the locking bolt into the locking bolt cage by any instrument they happen to have at hand. Speed of movement at the initiation thereof is desirable not only for the reason just stated but to prevent a prisoner from forcing the door open before the locking bolt engages the locking cage.

Various other objects and advantageous features of my invention will be seen in the follow-

ing description and one embodiment thereof may be seen in the accompanying drawing wherein similar characters of reference designate corresponding parts, and wherein:

Fig. 1 is a top plan view of a lock constructed in accordance with my invention; Fig. 2 is a plan view showing the locking bolt and lock actuating cam with the locking bolt in full retracted or unlocked position; Fig. 3 is a fragmentary view similar to Fig. 2 but showing the locking bolt in a partly projected or locked position; Fig. 4 is a view similar to Fig. 3 showing the locking bolt in full projected or locked position; Fig. 5 is a view, partly in section and partly in elevation, of the lock mechanism shown in Fig. 1; Fig. 6 is a view taken on the line 6—6 of Fig. 5; and Fig. 7 is a view showing the key employed for actuating the lock mechanism and lock bolt.

As shown in the drawing, one suitable embodiment of my invention takes the form of a lock that consists of a base plate or casting 1 providing a means for securing the lock mechanism to a suitable support. For instance, the base plate or casting may be welded permanently along its edges to a metal plate of a wall or to a door. Such plate carries the operating parts of the lock mechanism, which mechanism is covered by a casing 2 attached to the plate 1 and the operating parts include a sliding lock bolt 3 having its locking portion guided in an opening in the wall of the casing 2, the bolt also having an elongated guiding slot or opening 4 through which extend movable lock actuating parts comprising a lever arm connector or roll back 5 having a portion thereof of sleeve form and journaled on an annular boss 6 rigidly mounted on the plate 1. The roll back or lever arm connector 5 also is provided with an upper cylindrical recess 6' into which extends the inner end of a cylinder 7 having a rotary plug 8 thereon provided with a non-circular driving projection 9 entering a corresponding socket 10 in the roll back or lever arm connector 5 for operating the same.

In accordance with my invention, the roll back or lever arm connector 5 is provided with compound cam surfaces or curvatures and lobes beginning at substantially diametrically opposite points on the edges of the hub portion thereof and terminating in a lobe spaced from the center of rotation of the roll back, all such curvatures and lobes being formed by arcs on centers different from each other and from the center of rotation of the roll back. These cur-

5 vatures and lobes of the roll back cooperate with curvatures and lobes on opposite side edges of the roll back opening, as shown, in such manner as to instantaneously move the bolt when
 10 the roll back is moved and to lock the bolt against movement by force exerted on the bolt and in the direction of bolt movement when the bolt is in locking position. It will be noted that surfaces on opposite sides of the roll back are
 15 in engagement with surfaces on opposite side edges of the bolt opening when the bolt is in full locked or full unlocked position whereby such instantaneous movement may be had.

Referring to Figs. 2, 3 and 4, the roll back or 15 lever arm connector 5 has a lobe 11 on one side of the hub thereof which continues in a curvature 12 which, in turn, terminates at a lobe 16 spaced a considerable distance from the hub of the roll back. The opposite side of the roll back 20 5 includes a curvature 15 beginning at the side of the hub of the roll back, and at a point substantially diametrically opposite the beginning of the lobe 11, and extending away from the hub to end at the lobe 16 hereinbefore mentioned. Such lobes and curvatures of the roll back are arranged whereby the general outline of the roll back is triangular with the center of rotation of the roll back in the base line of the triangle and the lobe 16 at the apex thereof.

30 As shown in the same Figures 2, 3 and 4, the curvatures and lobes provided on opposite end edges of the roll back opening 4 include, on the right hand side as viewed in the above figures, a curvature 13 beginning at the bottom of the opening 4, and below the hub of the roll back 5, and extending above the hub of the roll back to end in a lobe 13'. A curvature 14 extends onward from the lobe 13' and away from the level of the hub of the roll back. On the 35 left hand side as viewed in the above figures, the curvatures and lobes include a curvature 17' beginning at the bottom of the opening 4 in the same horizontal plane as the beginning of the curvature 13 of the opposite side and extending upwardly above the hub of the roll back to end in a lobe 17, a curvature 18 extending outwardly from the lobe 17 and away from the level of the hub of the roll back. The curvatures 13 and 17' are hereinafter referred to as 40 being substantially aligned with the center of rotation of the roll back and the curvatures 14 and 18 are referred to as being offset from said center.

The curvatures 13 and 17' have substantially 55 the same radius as that of the hub portion of the roll back whereby in either full locked or full unlocked position of the bolt, the opposite sides of the roll back nest in either one or the other of such curvatures. It will be noted that 60 the curvatures 14 and 18 are so arranged and the lobe 16 is so shaped and spaced from the center of rotation of the roll back that in full unlocked position, see Fig. 2, the lobe 16 nests in the curvature 14 while the opposite edge of 65 the roll back is nesting in the curvature 17', and that when in full locked position, see Fig. 4, the lobe 16 is engaged in the curvature 18 while the opposite edge of the roll back is nested in the curvature 13. These curvatures and lobes are 70 also so arranged that when the bolt is in full locked position the lobe 16 and the bearing surface between the lobe 11 and the curvatures 13 are so nearly parallel with each and with the line of movement of the bolt toward unlocked 75 position that the bolt is held in locked position

against movement toward unlocked position through force exerted on the bolt in the direction of its line of movement.

With the above arrangement of curvatures and lobes on the roll back and bolt opening, initial movement of the locking bolt 3 will be accomplished with maximum power and speed 80 since the curvature 15 begins at the hub of the roll back or lever arm connector 5. Continued movement of the roll back or lever arm connector 5 in a contra-clockwise direction will 85 result in the curvature 15 leaving the curvature 17' and lobe 17, as shown in Figs. 3 and 4, and the lobe 16 contacting with the curvature 18 to move the locking bolt into full locked position, 90 although with substantially less power than results from the co-action of the curvature 15 and curvature 17' and lobe 17. However, at this time, the locking bolt will have entered its locking cage, which will effectively prevent the 95 prisoner from blocking movement of the locking bolt by the insertion of some instrument between the outermost end of the locking bolt and the mouth of the locking cage so maximum power is no longer necessary. The lobe 16 and 100 curvature 18 also provide auxiliary cam means that would be effective to move the locking bolt to full locked position even though the curvature 15 and lobe 17 were entirely worn away.

I have shown a locking mechanism of the 105 rotary plug and cylinder type as disclosed in my co-pending application, Serial No. 536,401, filed May 11, 1931, to which reference may be had for details of the lock mechanism not herein described. However, it will be understood that 110 other types of locking mechanism are equally applicable. As in this preceding application, the casing or cover 2 includes an annular boss 19 presenting a sleeve portion in the socket or recess of which the cylinder or barrel 7 is 115 mounted, the cylinder or barrel having an annular flange 21 that rests on a shoulder 22 in the sleeve. Such cylinder or barrel fits loosely within the sleeve, and the annular flange is provided with openings adapted to fit over pins 23 extending outwardly from the shoulder 22 whereby the cylinder or barrel is held against rotation but may be easily inserted into or removed from the sleeve. The plug 8 fits loosely within the cylinder or barrel 7 and is rotatable relative thereto, 120 being held within the cylinder or barrel by means of an annular plate 24 that is held on the annular flange of the cylinder or barrel by means of screws 26. The plate 24 fits over the plug 8 and abuts against an annular shoulder 125 thereon.

Suitable means are provided for confining the cylinder and plug within the sleeve. As shown, the cylinder and plug are confined in the sleeve by a washer 27 threaded into the outer end of 130 the sleeve and doweled into the cylinder or barrel by means of pins 28 that extend through openings in the washer 27 and into corresponding openings in the cylinder or barrel. After the parts have been properly assembled, the outermost ends of the pins 28 may be ground off flush with the outer face of the washer which effectively prevents removal of the washer and other parts of the locking mechanism except by an authorized person with proper equipment.

The plug 8 is provided with a cruciform key-way or slot 29 for a key 30 having ward portions of like cross section which actuate tumbler levers 31 that cooperate with longitudinal 135 grooves 32 of the cylinder or barrel 7 and nor-

5 mally prevent rotation of the plug relative to the cylinder or barrel. At its top, the plug 8 is provided with a non-circular socket or recess 33 to receive a like-shaped portion 34 of the key 30 when the latter is fully inserted in the key-way in the plug 8. This construction permits the operating power of the key to be taken from the portion 34 thereof instead of from the wards, which protects the wards against injury 10 as well as preventing the key from being inserted into the lock in any but one position.

In the operation of this lock mechanism, the key 30 is first inserted into the locking mechanism of the cylinder and plug type which moves 15 the tumbler levers 31 out of the slots 32 and permits the plug 8 to be rotated within the cylinder or barrel 7 on turning the key. With the construction of the lock actuating parts hereinbefore described, and since the plug is 20 provided with a non-circular driving projection 9 that fits within a corresponding socket 10 in the roll back or lever arm connector 5, turning of the key and plug will result in instantaneous movement of the locking bolt toward either its 25 locked or unlocked position, the cam surfaces on the roll back or lever arm connector and the cam surfaces in the elongated slot or opening 4 being so arranged that the first operating cam surfaces on opposite sides of the roll back or 30 lever arm connector and elongated guiding slot or opening are brought into a position to immediately co-act with each other when the locking bolt is positioned in its full locked or unlocked position respectively. This is clearly 35 shown in Figs. 2 and 4.

Referring to Figs. 1 and 6 of the drawing, it will be seen that the parts, including the cylinder 7 and plug 8, are so arranged that the non-circular opening 33 for receiving the part 34 of the key is normally disposed at an angle to the transverse axis of the lock mechanism, when the locking bolt is in full unlocked or locked position. This is an advantageous feature in that it provides a means for indicating whether 45 or not the locking bolt is in full locked or full unlocked position without requiring insertion of the key which has heretofore been necessary. In other words, a mere glance is sufficient to tell the position of the locking bolt.

50 Referring to the drawing and the preceding description, it will be seen that I have provided a lock mechanism that is particularly adapted for use on confinement cells or corridor doors of prisons wherein the operating key moves only 55 through an arc of 90° and wherein initiation of movement of the key causes instant initiation of movement of the locking bolt toward either full unlocked or locked position, depending upon the direction of movement of the key. 60 The advantageous features resulting from this type of lock are readily apparent from the preceding description.

What I claim is:

1. Lock mechanism comprising, a lock bolt, a 65 roll back rotatable about a center, said lock bolt having an opening in which the roll back operates, said opening having two cam surfaces on each of its end edges, one cam surface on each end edge being substantially aligned with the roll back center and the other cam surface 70 on each end being offset from said center, and said roll back having cam surfaces arranged to coact alternatively with the cam surfaces on either edge of the bolt opening for producing 75 bolt movement, the roll back cam surfaces being

constructed and arranged to coact successively with the aligned and offset cam surfaces.

2. Lock mechanism comprising, a lock bolt, a roll back rotatable about a center, said lock bolt having an opening in which the roll back operates, said opening having two cam surfaces on each of its end edges, one cam surface on each end edge being substantially aligned with the roll back center and the other cam surface on each end being offset from said center, and said roll back having cam surfaces arranged to coact alternatively with the cam surfaces on either edge of the bolt opening for producing bolt movement, the roll back coacting successively with the aligned and offset cam surfaces, and two of the cam surfaces on said roll back being offset relative to each other from the center of movement of said roll back and arranged to be disposed substantially in a line parallel to the line of bolt movement and in coacting relation with the offset surface of one edge and the aligned surface of the other edge when the bolt is in full locked position.

3. Lock mechanism comprising, a lock bolt, a roll back rotatable about a center, said lock bolt having an opening in which the roll back operates, said opening having two cam surfaces on each of its end edges, one cam surface on each end edge being substantially aligned with the roll back center and the other cam surface on each end being offset from said center, and said roll back having cam surfaces arranged to coact with different pairs of said cam surfaces on opposite edges of the bolt opening in full locked and unlocked positions respectively, each pair of surfaces comprising an aligned surface on one edge and an offset surface on the other edge.

4. Lock mechanism comprising, a lock bolt, a roll back rotatable about a center, said lock bolt having an opening in which said roll back operates, the roll back being movable through 90° to produce full locked or full unlocked positions of said bolt, said opening having two cam surfaces on each of its end edges, one cam surface on each end edge being substantially aligned with the roll back center and the other cam surface on each end edge being offset from said center, and said roll back having cam surfaces arranged to coact alternatively with the cam surfaces of either edge of the bolt opening for producing bolt movement, the roll back coacting successively with the aligned and offset cam surfaces, and said roll back surfaces being arranged to coact with different pairs of said cam surfaces on opposite edges of the bolt opening in full locked and unlocked positions respectively, each pair of surfaces comprising an aligned surface on one edge and an offset surface on the other edge.

5. Lock mechanism comprising, a lock bolt, a roll back rotatable about a center, said lock bolt having an opening in which the roll back operates, said opening having cam surfaces on each of its end edges substantially aligned with the roll back center, a first aligned surface toward the locking end of the bolt and a second aligned surface opposite the first, said opening also having a cam surface on the locking end edge offset from said center, said offset cam surface being concave toward the roll back, said roll back having cam surfaces arranged to coact with the cam surfaces of the opening for producing bolt movement, the side of the roll back adapted to coact with the locking end edge of said bolt opening having a portion of its cam-

ming surface arranged to contact the first aligned surface during initial movement of the bolt toward locking position and having another portion of its camming surface adapted to rest 5 against the offset cam surface when the bolt is in full locked position, and the side of said roll back away from the locking end of the bolt having a surface adapted to contact said second aligned surface when the bolt is in full locked 10 position.

6. Lock mechanism comprising, a lock bolt, a roll back rotatable about a center, said lock bolt having an opening in which the roll back operates, said opening have two cam surfaces on its 15 edge toward the locking end of the bolt and a cam surface on its opposite edge, the first-named surfaces comprising one aligned with the roll back center and one offset from said center, and said roll back having surfaces so arranged about 20

its center that the roll back contacts the offset cam surface and the cam surface on the opposite edge when the parts are in full locked position.

7. Lock mechanism comprising, a lock bolt, a roll back rotatable about a center, said lock bolt having an opening in which the roll back operates, said opening having two cam surfaces on its edge toward the locking end of the bolt and a cam surface on its opposite edge, the first-named surfaces comprising one aligned with the roll back center and one offset from said center, and said roll back having surfaces so arranged about 80 85 90 its center that the roll back contacts the aligned cam surface and the cam surface on the opposite edge when the parts are in full unlocked position.
